(57) **CLAIM**

The ornamental design for a collapsible power saw bench, as shown and described.

DESCRIPTION

FIG. 1 is a front right isometric view of a collapsible power saw bench showing my new design.

FIG. 2 is a right side elevational view thereof.

FIG. 3 is a front elevational view thereof.

FIG. 4 is a rear elevational view thereof.

FIG. 5 is a top plan view thereof; and,

FIG. 6 is a bottom plan view thereof.

The portions of the design shown in phantom lines are for environmental purposes only and form no part of the claimed invention.
